UNITED STATES PATENT OFFICE

118,230

DESIGN FOR A PLANT BOX

William Fader, Newark, N. J.

Application October 4, 1939, Serial No. 87,496

Term of patent 7 years

To all whom it may concern:

Be it known that I, William Fader, a citizen of the United States, residing at Newark, in the county of Essex and State of New Jersey, have invented a new, original, and ornamental Design for a Plant Box, of which the following is a specification, reference being had to the accompanying drawing, forming part thereof.

I claim:

The ornamental design for a plant box, as shown.

WILLIAM FADER.
